(57) **CLAIM**

The ornamental design for a fish line worm threader, as shown and describe.

DESCRIPTION

FIG. 1 is a top perspective view of my new design for a fish line worm threader.

FIG. 2 is a front elevation view thereof;

FIG. 3 is a back elevation view thereof;

FIG. 4 is a left side elevation view thereof;

FIG. 5 is a right side elevation view thereof;

FIG. 6 is an enlarged top plan view thereof;

FIG. 7 is an enlarged bottom plan view thereof;

FIG. 8 is an exploded, top perspective view thereof; and,

FIG. 9 is a top perspective view in use thereof.

The broken lines depicting a fishing line in FIG. 1, and a fishing line, worm and a hook in FIG. 9 illustrate environment that forms no part of the claimed design.
